UNITED STATES PATENT OFFICE.

GEORGE C. JENSEN, OF OAKLAND, CALIFORNIA.

LOCK DEVICE FOR GEAR-SHIFT LEVERS.

1,262,348.

Specification of Letters Patent.

Patented Apr. 9, 1918.

Application filed February 13, 1918. Serial No. 216,966.

To all whom it may concern:

Be it known that I, GEORGE C. JENSEN, a citizen of the United States, residing at Oakland, in the county of Alameda and State of California, have invented certain new and useful Improvements in Lock Devices for Gear-Shift Levers, of which the following is a specification.

The present invention relates to an improved locking device for levers, and has for its principal object to provide a construction capable of attachment to a lever housing through an opening formed therein, and when in operative position for engaging the lever to prevent the same from operative movement, precluding the removal of the same from its mounting, and at the same time maintaining the locking construction locked within the lever mounting.

The invention consists primarily in a locking unit adapted for threaded attachment to a lever mounting and provided with a locking bolt, preferably arranged at right angles to the lever, and capable of seating, when in locked position, in a depression within the lever to maintain the lever against a stop to prevent operative movement thereof and to preclude removal of the lever from its mounting.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention reference should be had to the accompanying sheet of drawings, wherein—

Figure 1 is a vertical sectional view of the preferred embodiment of my invention.

Fig. 2 is a sectional view taken on line 2—2 Fig. 1 of the drawings and viewed in the direction of the arrows.

In the drawings, 1 indicates a suitable tubular lever support provided at its upper end with a socket portion 2 for reception of the spherical portion 3 formed intermediate the end of the lever 4 extended downwardly through the tubular support 1.

The support 1 is provided, adjacent the socket portion, with vertical grooves 5, in which are received laterally extending lugs 6 projecting from the spherical portion 3, said lugs preventing axial rotation of the lever within its support. A ring 7 surrounding the lever and having threaded connection with the support 1 above the socket portion 2, bears downwardly on the spherical portion 3 and maintains said lever fulcrumed in the support 1.

A suitable guard or protecting cup 8 is carried by the lever above the spherical portion 3 and the same operates over the upper end of the support 1 to prevent the entrance of foreign material into the fulcrum connection of the lever.

Below the spherical portion 3, the lever is provided in one side with a laterally disposed recess or opening 9, and said lever at a point below said fulcrum is adapted to contact with a stop 10 projecting inwardly from the inner surface of the support 1.

At a point opposite said stop 10, and slightly above the same, the support 1 is provided with a threaded opening 11 adapted to receive the inner threaded end of a mounting 12 which is adapted for threaded attachment thereto. The mounting 12 is provided with a flange 13 for contacting with the surface of the opening 11 to limit the inward movement of said mounting.

Formed in the mounting and disposed to lie at substantially right angles to the lever 4, and facing said recess or opening 9, is a bore or channel 14 opening at its inner end, as at 15, and within which is mounted the longitudinally movable locking bolt 16, the inner end of which is adapted, when the bolt is in locking position, to project into the recess 9 and engage the lever to prevent movement of the same, and to retain the said lever in contact with the stop 10.

The opening 11 is provided at its lower point with the offset 17, within which the inner end of the bolt projects when the same is moved to locking position, as in Fig. 1 of the drawings, and the bolt when in such position preventing the unthreading of the mounting 12 from the support 1.

The undersurface of the bolt 1, adjacent the inner end thereof, is undercut, as at 18, thus requiring but a slight rearward movement of the bolt to enable the reduced

end 19 thereof to clear the wall of the opening 11 and enable the mounting 12 to be detached from the support 1, and thus reducing the necessary stroke of the operating plunger.

The bore or channel 14 is provided at its rear end with a comparatively small opening 20, in which is adapted to slide the operating plunger 21 extended rearwardly 10 from the rear face of the locking bolt 16, and of a diameter less than said bolt, thereby providing a stop surface 22 at the rear face of the bolt for contacting with the rear wall of the bore or channel 14 to limit the 15 rearward movement of the locking bolt therein. The locking bolt 19 is provided with a longitudinally disposed spring receiving bore 23 in which is extended one end of a coiled spring 24, secured at one 20 end to said bolt, and at its opposite end fastened to the rear wall of the channel 14.

The upper peripheral surface of the locking bolt 16 is provided with a notch 25, in which is adapted to be received the lower 25 reduced end 26 of a longitudinally movable latch 27 mounted in a bore 28 arranged preferably at right angles to the bore 14, and terminating at its outer end through the peripheral surface of the mounting 12. 30 The latch 27 is normally forced into contact with the bolt 16 by a coiled spring 29, mounted in a bore 30 in the mounting 12.

Arranged at right angles to the latch 27, and disposed parallel with the locking bolt 35 16, is a locking barrel 31, preferably of the key-controlled type, and provided with the rotatable tumbler 32, carrying an eccentric end or finger 33 which is received in a notch or cutout 34 in the side wall of the latch 27. 40 It will be apparent that on the rotation of the tumbler 32, the same will raise the latch 27 and withdraw the end 26 thereof from the notch or recess 25 in the locking bolt 16, which will enable the spring 24 to withdraw 45 said bolt into the bore or channel 14 and remove the outer or reduced end thereof from the recess or depression 9 in the lever 4.

My improved construction is designed for 50 interrupting the circuit of the ignition system when the locking bolt is in locking or operative position, and in carrying out this feature, a circuit is formed through the attachment of the wire 35 with the mounting 12 and the securing of the other wire 36 of 55 the circuit to a suitable post 37 having a spring-pressed contact or brush member 38 mounted therein, which is adapted, when the bolt 16 is in retracted or unlocked position, to contact with the surface thereof and 60 complete a circuit therethrough. The bolt is provided with an insert of insulating material 39 with which the brush 38 is adapted to contact on the movement of the bolt 16 into locking position, as in the drawing, 65 thus interrupting or breaking the circuit

between the wires 35 and 36. A suitable insulating plug or member 40 mounts the post 37 and secures the same to the mounting 12 through a threaded bore therein.

By my improved construction I am enabled to automatically interrupt the ignition circuit of the motor when the lever is locked in inoperative position.

Having thus described my invention, what I claim as new and desire to protect by Letters Patent is:

1. A mechanism for detachably securing to a lever casing and to coöperate with the lever through an opening in the casing to lock the lever from operative movement, the same comprising a lock casing or mounting 70 for detachably securing to the lever casing, a longitudinally movable bolt carried thereby for coöperation with the lever through said opening in the lever casing to lock the lever from movement, means for locking the bolt in coöperative relation with the lever, said bolt when in locking position intersecting the lever casing to lock said lock casing from detachment from the lever casing, the inner end of said bolt being reduced, whereby by the same will clear said lever casing on a slight movement of the bolt to admit of the detachment of the locking casing from the lever casing on the releasing of said bolt. 95

2. In combination with a lever casing, a lever removably fulcrumed therein for universal swinging movement, said casing provided with an opening in its wall below the fulcrum point of said lever and formed with a stop lying opposite said opening and with which said lever contacts when in its neutral position, said lever provided in its side wall at a point facing said opening with a laterally opening depression, and a longitudinally movable lock controlled locking bolt supported in said opening and capable of longitudinal movement for reception at its inner end within said depression to maintain said lever in contact with said stop, thereby preventing operative movement of the lever on its fulcrum or removal of the same therefrom. 100

3. In combination with a lever casing, a lever removably fulcrumed therein for universal swinging movement, said casing provided with an opening in its wall below the fulcrum point of said lever, and formed with a stop lying opposite said opening and with which said lever contacts when in its 115 neutral position, said lever provided in its side wall at a point facing said opening with a laterally opening depression, a longitudinally movable lock controlled locking bolt supported in said opening and capable of longitudinal movement for reception at its inner end within said depression to maintain said lever in contact with said stop, thereby preventing operative movement of the lever on its fulcrum or removal of the 120

125

130

same therefrom, an electrical contact member carried by said casing and insulated therefrom and adapted to contact with the locking bolt to complete a circuit there-through when the bolt is in its unlocked position, and an insulating portion carried by said locking bolt for contacting with said contact member on the movement of said bolt to locking position, whereby the circuit therethrough is broken on the locking of said lever from movement.

4. In combination with a lever casing, a lever removably positioned therein and fulcrumed therein for universal swinging movement, said casing provided below the fulcrum point of said lever with an opening in its side wall, and formed with a stop lying opposite said opening and with which said lever contacts when in its neutral position, said lever provided in its side wall at a point facing said opening with a lateral opening depression, a lock casing or mounting for detachably securing to said lever casing through said side wall opening, a longitudinally movable locking bolt there-

in and capable of movement for reception at its inner end within said depression to maintain said lever in contact with said stop, thereby preventing operative movement of the lever on its fulcrum or removal therefrom, said bolt when in locking position intersecting said lever casing to lock said lock casing thereto, an electrical contact member carried by said lock casing and insulated therefrom and adapted to contact with said locking bolt to complete a circuit there-through when the bolt is in its unlocked position, and an insulating portion carried by said locking bolt for contacting with the said contact member on the movement of said bolt to locking position, whereby the circuit therethrough will be broken on the locking of said lever from movement.

In testimony whereof I have signed my name to this specification in the presence of two subscribing witnesses.

GEORGE C. JENSEN.
